SHUTTLE-TYPE PICTURE VIEWER

John H. Weggeland, P.O. Box 204,
Lehigh Acres, Fla. 33936

Filed Nov. 4, 1970, Ser. No. 25,831

Term of patent 14 years

Int. Cl. D16—03

U.S. Cl. D61—1

FIG. 1 is a front perspective view of a shuttle-type picture viewer showing my new design;

FIG. 2 is a right side elevational view thereof, the left side being substantially plain; and

FIG. 3 is a top plan view thereof on a reduced scale, with the shuttle in an extended position.

I claim:

The ornamental design for a shuttle-type picture viewer, substantially as shown and described.
